DESIGN FOR A BOTTLE

Annette Marquis, New York, N. Y., assignor to
Babs Creations, Incorporated, New York, N. Y.,
a corporation of New York

Application March 26, 1942, Serial No. 106,333

Term of patent 14 years

To all whom it may concern:

Be it known that I, Annette Marquis, a citizen of the United States, residing in New York city, in the county of New York and State of New York, have invented a new, original, and ornamental Design for a Bottle, of which the following is a specification, reference being had to the accompanying drawing, forming a part thereof.

In the drawing:

Figure 1 is a front elevational view of the bottle showing my new design, and

Figure 2 is a top plan view.

The drawing is shaded to show color.

I claim:

The ornamental design for a bottle, as shown and described.

ANNETTE MARQUIS.
